[57] ABSTRACT

An automatic winding mechanism for a watch movement with a unidirectional clutch comprising a cup-shaped wheel having inner and outer teeth, an element movable within the wheel transverse to the axis of rotation for transferring the winding weight to the inner teeth of the cup-shaped wheel.

FIG. 1

FIG. 2

FIG. 3

AUTOMATIC WINDING MECHANISM FOR WATCH MOVEMENTS

This invention relates to an automatic winding mechanism for watch movements, comprising a support, an arbor pivotally mounted on the support, a winding weight integral with the arbor, a winding gear-train, and a unidirectional clutch device coaxial with the arbor, the first gear of the gear-train being a reduction gear, and the clutch device connecting the arbor to the reduction gear so as to drive the gear-train when the weight rotates in a predetermined direction.

Winding mechanisms of this kind are already known. They present the particularity that the movements of the winding weight are utilized to wind the mainspring only when the weight moves in a certain direction, whereas the weight idles when it rotates in the opposite, non-winding direction. Although mechanisms of this kind have been known for many years now, it was long thought preferable to construct mechanisms equipped with a reverser instead of the unidirectional clutch in order to utilize the movements of the weight regardless of their direction. The development of winding mechanisms with unidirectional clutches was not pursued, and the unidirectional clutches of winding mechanisms winding in only one direction still present numerous drawbacks. In particular, these known mechanisms comprise coupling members with resilient tongues which exert axially directed forces upon the arbor of the winding weight, and this tends to brake the movements of the weight. Moreover, the reliability of these known clutches leaves something to be desired.

It has recently been realized that automatic winding mechanisms winding in only one direction and equipped with a unidirectional clutch coaxial with the arbor are sufficiently effective for winding the mainspring and are, at the same time, simple and robust, thus making it possible to reduce the cost price of the winding mechanisms while ensuring that the automatic winding operation is carried out perfectly well. However, the use of such an arrangement has necessitated the provision of a reliable and compact unidirectional clutch with good efficiency.

The object of the present invention is therefore to provide an automatic winding mechanism of the type which winds in only one direction and which is equipped with such a unidirectional clutch.

To this end, in the automatic winding mechanism according to the present invention, the support comprises two parallel elements guiding the arbor at two different levels, and the unidirectional clutch device comprises, disposed between the support elements, a wheel mounted loose on the arbor and having a cupped portion, an outer toothed, and an inner toothed, and a bolt which is situated in the cupped portion, is integral in rotation with the arbor, and is adapted for translatory motion perpendicular to the axis of the arbor, the bolt cooperating with the inner toothed to make the arbor and the wheel integral upon rotation of the winding weight in the predetermined direction.

Furthermore, it is known that in order to keep the mainspring of a watch movement wound, it is necessary to provide a blocking member which allows the barrel-arbor to rotate in the winding direction but blocks it in the unwinding direction. Mechanisms of various forms have already been used for this blocking device, e.g., a click-pinion having a toothed shaped in such a way as

to block the ratchet-wheel integral with the barrel-arbor when the ratchet-wheel tends to rotate in the unwinding direction, but allowing rotation in the winding direction. Devices have likewise been proposed which comprise a bolt mounted on the barrel-arbor and moving transversely under the influence of centrifugal force when the arbor tends to rotate. The latter devices were abandoned long ago, however, and only the click devices are currently used.

10 In one embodiment of the present invention, the retaining device for the barrel-arbor comprises a click-pinion which cooperates with the wheel-toothing of one of the gears, preferably the first one, of the multiplying gear-train of the automatic winding mechanism.

15 A preferred embodiment of the invention will now be described in detail with reference to the accompanying drawings, in which:

FIG. 1 is a top plan view of the mechanism.

FIG. 2 is a section taken on the line II—II of FIG. 1, and

FIG. 3 is a section taken on the line III—III of FIG. 1.

20 The automatic winding mechanism illustrated in the drawings is designed to be manufactured and mounted as a self-contained assembly which may be fitted as a single unit on the back surface of a watch movement. Part of this watch movement is shown in FIG. 2, where a frame element 1 is visible, constituting a wheel-train bridge, for example. The drawing also shows a ratchet-wheel 2 which is integral with a barrel-arbor as in any conventional watch movement. The automatic winding assembly comprises a support formed of two bridges 3 and 4 which are mutually adjusted by means of two pins

25 5 and 6 and secured to one another by a screw 7 passing through the bridge 4 and the thickest portion of the bridge 3. The pins 5 and 6 are driven into the bridge 4 and engaged without play in corresponding openings in the bridge 3. They project out of the bridge 4 so as to

30 35 be able to engage in openings 8 in the bridge 1, thus ensuring the proper positioning of the assembly on the movement. The assembly is secured by means of two screws 9, the heads of which are countersunk in recesses in the outer surface of the bridge 3.

40 45 The ratchet-wheel 2 is automatically wound by means of a rotary weight 10, a portion of which is shown in FIG. 2. The weight 10 is integral in rotation with an arbor 11, to which it is secured by means of a rigid disc 12 and a resilient disc 13. The resilient disc

50 55 13 has a circular central opening; it is engaged in a circular recess in the winding weight 10 and around a protruding head of the arbor 11 and is held in place by the rigid disc 12, which has a keyhole-shaped opening engaging under the protruding head of the arbor 11 and being blocked under that head.

55 60 Thus the weight 10 and the arbor 11 are rigidly connected as long as the torque exerted by the weight 10 does not exceed a given limit. When that limit is reached, the weight 10 can slide beneath the resilient disc 13, thus protecting the transmission mechanism.

65 As a variation, however, any other rigid fixing means might be provided between the weight 10 and the arbor 11 which would cause the arbor 11 to rotate when the weight 10 moves owing to its heaviness or inertia. A cylindrical bearing surface 14 of the arbor 11 pivots in a circular opening in the thinnest portion of the bridge 3, and a pivot-shank 15 at the end of the arbor 11 remote

from the weight 10 pivots in a corresponding opening in the bridge 4.

The movements of the oscillating weight 10 and of the arbor 11 are transmitted to the ratchet-wheel 2 by a gear-train comprising a first wheel-and-pinion 16 coaxial with the arbor 11. This wheel-and-pinion consists of a pinion 17, engaged on a cylindrical bearing surface 18 of the arbor 11, and a ring-wheel 19 which has an inner tooth 19a and is secured to the pinion 17. The inner tooth 19a has an odd number of slightly spaced triangular teeth, as may be seen in FIG. 1. The pinion 17 meshes with the wheel of a speed-reducer wheel-and-pinion 20 which pivots between the bridges 3 and 4, and the pinion of which is engaged with the wheel of a wheel-and-pinion 21. The latter pivots on a fixed pin 22 driven into an opening in the bridge 3 and is held in place axially by an annular rib 23 stamped in the inner surface of the bridge 4 coaxially with the pin 22. The bridge 4 also has a circular opening 24 within the rib 23 so that the pinion of the wheel-and-pinion 21 and the end of the pin 22 can project out of the assembly in such a way that the tooth of the pinion of the wheel-and-pinion 21 meshes with the ratchet-wheel 2. The wheel of the wheel-and-pinion 20 cooperates with a retaining click-pinion 29 (FIG. 3), the teeth of which are engaged with that wheel. The click-pinion 29, which has an asymmetrical tooth, pivots on a stud 30 projecting from the inner surface of the bridge 3. It is held in place between the bridges 3 and 4 and protrudes into respective openings 31 and 32 in these bridges, the first opening constituting an inspection hole and the second an oiling hole.

In the embodiment illustrated in the drawings, the asymmetry of the teeth of the pinion 29 is such that if the wheel of the wheel-and-pinion 20 rotates counter-clockwise, as viewed in FIG. 1, two adjacent teeth of the pinion 29 simultaneously come in contact with two adjacent teeth of the wheel 20, and the gearing is blocked by the pressure of the apex of one of the teeth of the click-pinion 29 on the arcuate apex of one of the teeth of the wheel 20. It will be noted that the arcuate apices of these teeth all lie on the circumference of a circle coaxial with the wheel 20. If the wheel 20 rotates clockwise, the relative positioning of the wheel 20 and the click-pinion 29 changes because their respective toothings are engaged with a relatively substantial amount of play. It is then the convex edge of a tooth of the click-pinion 29 which is pushed by the flank of a tooth of the wheel 20. Blocking is no longer possible, and the click-pinion 29 is driven rotatably. It will likewise be noted that in this embodiment of the click system, the teeth of the wheel 20 are symmetrical. Moreover, the use of the click-pinion described makes it possible to eliminate the click-spring which would be indispensable with a conventional retaining device.

For the purpose of driving the ratchet-wheel 2 from the arbor 11 when the latter rotates in a predetermined winding direction, the mechanism described here further comprises a unidirectional clutch device between the pinion 17 and the arbor 11. The elements of this clutch device are as follows: the lower portion of the bearing surface 18 has two parallel flat portions 25, so that its cross-section through a plane perpendicular to the arbor 11 has the shape of a rectangle with rounded ends. As may be seen in FIG. 2, the flat portions 25 are on the same level as the inner tooth 19a of the ring-wheel 19. Interposed between the flat portions 25 and

the tooth 19a is a bolt 26 consisting of an elongated flat plate blanked in the shape of a rectangle with rounded ends and having two beaks 27 and 28, directly opposite one another and projecting outward from the respective centers of the two rounded ends. The bolt 26 also has a central opening comprising two straight edges, the space between them being equal in width to the distance between the two flat portions 25, and the length of the space being greater than the diameter of the bearing surface 18. The ends of the two straight edges are joined by edges having the shape of arcs of a circle with a slightly greater radius than that of the bearing surface 18, so that the bolt 26 can move transversely to the axis of the arbor 11 until one or the other of the ends of its opening comes up against the bearing surface 18. Moreover, as the width of this opening is adjusted to the distance between the flat portions 25, the bolt 26 and the arbor 11 are rotatably coupled. As for the beaks 27 and 28, their dimensions are such that, whatever the position of the bolt 26, one of them is engaged with the tooth 19a.

Therefore, as may be seen in FIG. 1, if the winding weight rotates clockwise, the bolt 26 oscillates on the bearing surface 18, for the beaks 27 and 28 are alternately pushed away by the backs of the teeth 19a. Thus the wheel-and-pinion 16 is not driven, for like the wheels-and-pinions 20 and 21, it is blocked by the click-pinion 29. The gear-train being blocked, the weight idles. As soon as the weight rotates counter-clockwise, on the other hand, one of the beaks 27 or 28 hooks into the radial flank of one of the teeth 19a, so that the wheel-and-pinion 16 and the arbor 11 are coupled. The pinion 17 drives the wheel-and-pinion 20 clockwise. The pinion of the wheel-and-pinion 20 drives the wheel of the wheel-and-pinion 21 counter-clockwise, so that the ratchet-wheel 2 is driven clockwise, the ratio of reduction between the speeds of rotation of the weight and the ratchet-wheel, respectively, being about 1:150. It will be noted that the ratchet-wheel 2 is likewise equipped with a conventional retaining click which prevents the mainspring from up-winding.

When the mainspring is wound by hand, the ratchet-wheel 2 is driven by a crown-wheel (not shown). The wheels-and-pinions 21 and 20 are likewise driven rotatably, as is the wheel-and-pinion 16. The direction of rotation of the latter wheel-and-pinion is such that the bolt 26 effects an oscillating movement in its plane, i.e., perpendicular to the axis of the arbor 11. Because of its great inertia, the winding weight does not move.

The winding mechanism described above presents numerous advantages. It is made up of elements which, like the bridges 3 and 4 and the various wheels and pinions described, may be easily machined. It will be noted in particular that all the holes in the bridges are circular ones, which considerably facilitates blanking. Moreover, the mechanism does not include any springs, and this simplifies manufacture by eliminating all the operations involved in the production of resilient blades having to conform to specified tolerances, as well as their inspection and testing. What is more, owing to these particularities, the mechanism is very easy to assemble. These operations are especially simplified by the fact that the springs comprised by the previously-known mechanism have been eliminated. The elimination of the springs also makes possible an improvement in the mechanical efficiency of the transmission. Finally, be-

cause the unidirectional clutch device of the mechanism described is mounted coaxially with the arbor 11, its size may be such that it operates reliably and is resistant to wear without its taking up too much space with respect to the rest of the mechanism.

A last advantage of the mechanism described here is that the automatic winding assembly as a whole is completely independent of the basic caliber. It thus enables the manufacture of movements to be carried out more efficiently by creating groups of related calibers. A basic caliber without automatic winding may be transformed into an automatic-winding movement simply by adding the assembly, without making any changes in the rest of the movement.

What is claimed is:

1. An automatic winding mechanism for watch movements, comprising a support, an arbor pivotingly mounted on said support, a winding weight integral with said arbor, a winding gear-train, and a unidirectional clutch device coaxial with said arbor, the first gear of said gear-train being a reduction gear, and said clutch device connecting said arbor to said reduction gear so as to drive said gear-train when said weight rotates in a predetermined direction, wherein said support comprises two parallel elements guiding said arbor at two different levels, and said clutch device comprises, disposed between said elements, a wheel mounted loose on said arbor and having a cupped portion, an outer tooth, and an inner tooth, and a bolt which is situated in said cupped portion, is integral in rotation with said arbor, and is adapted for translatory motion perpendicular to the axis of said arbor, said bolt cooperating with said inner tooth to make said arbor and said wheel integral upon rotation of said weight in said predetermined direction.

2. A winding mechanism in accordance with claim 1, wherein said arbor comprises a projecting collar and an annular shoulder which determine the axial position of said arbor between said elements, and said wheel is axially held in place by said collar and by an inner surface of one of said elements.

3. A winding mechanism in accordance with claim 1, further comprising a unidirectional blocking device

which acts upon a tooth of a gear of said gear-train.

4. A winding mechanism in accordance with claim 3, wherein said blocking device comprises a click-pinion having an asymmetrical tooth engaged in said tooth of a gear and so disposed that two of its teeth block said gear by butting upon rotation of said gear in one direction, whereas said click-pinion is rotatably driven upon rotation of said gear in the opposite direction.

5. A winding mechanism in accordance with claim 1, 10 wherein said arbor and the gears of said gear-train are borne by said elements, and said elements are secured to one another and constitute an assembly, said assembly comprising means for positioning it upon and securing it to a watch movement.

15 6. A winding mechanism in accordance with claim 5, wherein the last gear of said gear-train comprises a pinion projecting out of said assembly and adapted to mesh with a ratchet-wheel when said assembly is positioned upon said watch movement.

7. A winding mechanism in accordance with claim 1, wherein said inner tooth is a wolf-tooth tooth, and said bolt comprises two beaks, each said beak being situated at a respective end of said bolt, said beaks cooperating alternately with said inner tooth.

8. A winding mechanism in accordance with claim 7, wherein said inner tooth comprises an odd number of teeth.

9. A winding mechanism in accordance with claim 7, 30 wherein said bolt consists of a flat plate having an elongated opening, and said arbor comprises a bearing surface having two flat portions on which said opening is engaged and which drive said bolt rotatably, the width of said opening being greater than the diameter of said bearing surface.

35 10. A winding mechanism in accordance with claim 9, wherein said opening comprises two straight, parallel edges and two arcuate end edges defining a space, the width of said space being equal to the distance between said flat portions, and the arcs defining said end edges being arcs of a circle having a radius greater than that of said bearing surface.
